WARP CONTROL IN POWER LOOMS

Albert Moessinger, Winterthur, Switzerland, assignor to Gebrueder Sulzer, Aktiengesellschaft, Winterthur, Switzerland

Application April 5, 1939, Serial No. 266,099
In Switzerland May 23, 1938

22 Claims. (Cl. 139—100)

The present invention relates to a warp supply and tensioning mechanism in looms for weaving more particularly to the "passive" type of such mechanism, i. e. whereby the mechanism is driven by the pulling action of the warp threads.

It is an object of the present invention to provide a mechanism of the type set forth in which the distance of the beaten up weft threads is exactly alike.

Another object of the present invention is the provision of a mechanism of the type set forth which is less expensive than the "active" type of warp supply mechanism and which operates accurately at all operating conditions of the warp beam, i. e. which is independent of the changing diameter of said beam.

It is an object of the present invention to provide a mechanism of the type set forth in which the warp beam is provided with a brake which brake is locked together with the warp thread tensioning beam during the beat.

According to the present invention the movements of the warp beam depend on a brake which is connected with the warp beam by means of a reducing gear and the warp threads are held under a desired tension by means of a warp tensioning beam. The tensioning beam and the brake are locked by the loom drive during the beat in the position in which they are before the beat and the brake is subjected to the action of the tensioning beam between the beats. Locking of the warp beam may be effected before or at least simultaneously with the locking of the tensioning beam. Locking of the brake and the tensioning beam may be effected by pressing the brake shoes for the tensioning beam against the brake disc also. In this case it is preferred that the line interconnecting the braking point of said brake and the axis of the tensioning beam and the line connecting the braking point and the center of the brake enclose an angle of approximately 90°. Locking of the warp beam may be accomplished by means of brake shoes which are parallel to the plane in which the lever moves which supports the tensioning beam. These brake shoes may simultaneously intensify the locking of the tensioning beam support lever. The brake may also be locked by periodic actuation of the brake band by means of the loom drive.

The spring acting on the tensioning beam support lever may be so arranged that the angle formed by the line interconnecting the point of action of said spring on said lever and the ful-

crum of said lever and the line of direction of the spring action is smaller than 60°. The initial tension of said spring is preferably equal to $r \tan \phi \sin \phi$, whereby r is the radius between the fulcrum of the tensioning beam support lever and the point of action of the tensioning spring on said lever and ϕ is the medium value of the above defined angle which should not exceed 60°. The adjustment of the moment of torsion exerted on the axis of the tensioning beam is preferably accomplished by displacement of the point of action of the tensioning spring on the tensioning beam support lever along a radius extending from the fulcrum of said lever. This displacement may be effected in a slot which is inclined approximately 45° with respect to the direction of the force of the tensioning spring. The slot may extend radially from the fulcrum of the tensioning beam support lever and the tensioning spring may be so mounted that its direction of action is moved parallel to itself when the spring is moved for changing the moment of torsion acting on said lever. If the direction of action of the tensioning spring on the tensioning lever remains parallel to itself when the warp tension is changed the angle ψ which is formed by the line of direction of action of the tensioning spring and the line along which the stationary end of the spring moves is

$$30 \quad \text{arc cot} \left(\tan \phi - \frac{1}{\tan \phi} \right)$$

The tensioning beam may be connected with the brake by means of a spring acting on the tension beam support lever under a desired angle and having a desired initial tension. The brake may be further subjected to the action of another spring or a weight which develops a force in the opposite direction of the force produced by the spring interconnecting the brake and the support lever. If the arrangement is so that the tension spring exerts on the support lever a moment of torsion in the opposite direction of the moment of torsion exerted by the brake spring the line of direction of action of the brake spring and the line between the point of action of the brake spring on the tensioning lever on the fulcrum of said lever should form an angle β which is smaller than 30°. According to the present invention the same spring may be used for tensioning the tensioning lever of the tensioning beam and for tensioning and actuating the brake.

Having now described in a general way some of the objects and principles of the present in-

vention, I now proceed in describing some specific embodiments of the present invention.

In the drawings:

Figure 1 is a diagrammatic side view of a mechanism according to the present invention.

Figure 2 is a top view of a detail of the mechanism shown in Fig. 1.

Figure 3 is an isometric showing of another detail of the mechanism shown in Fig. 1.

Figure 4 is a diagrammatic side view of a modified mechanism according to the present invention.

Figure 5 is a diagrammatic rear view of certain parts of the mechanism shown in Figure 4.

Figure 6 is a large scale view of a detail of the tensioning means and of a modification of a brake arrangement in a mechanism according to the present invention.

Figure 7 is a diagram showing spring forces acting on the brake of a mechanism according to the present invention.

Figure 8 is a large scale view of a modified tensioning arrangement according to the present invention.

Figure 9 is a large scale view of another modification of a tensioning means arrangement in a mechanism according to the present invention.

Referring more particularly to Figs. 1 to 3 of the drawings, 2 designates the warp beam from which the warp threads 1 are unwound; threads 1 pass over the tension roller or beam 4 before forming the shed with its point 3. The weft threads are pressed into the shed by means of the reed 3' whereby the material is produced which is passed over the breast beam 5 and wound to a cloth winding roller. The tensioning beam 4 rotatably rests at both ends on pivots 8 which pivots are supported by means of tensioning beam support levers 7. Levers 7 are rigidly interconnected by means of a tube or rod 6 and swing about the pivots 9. At least one of the levers 7 is connected with a brake comprising brake band 14, tensioning means 15 which may be connected to one of the pivots 8, and a brake drum 16. At least one of the levers 7 is held under tension by means of a spring 11 one end of which is stationary and the other acts on the connecting rod 10 which is adjustably and movably connected with the lever 7. The spring or springs 15 is or are preferably so positioned that the momentum acting on the tensioning levers is about the same at all normal possible positions of the lever.

Brake drum 16 is rigidly connected with a shaft 19 which rotatably rests in bearings 17 and 18. As can be seen in Fig. 3 shaft 19 also carries a disc 20 and a pinion 21. Pinion 21 engages a tooth wheel 22 which is rigidly connected with the warp beam 2. Each revolving motion of the warp beam is therefore transmitted to shaft 19 and brake disc 16. The warp beam shaft 23 rests in two bearings.

At least one of the tensioning beam levers 7 is provided with an extension 7' to which two plate members 24 are connected between which part of the disc 20 is located. A stirrup or inverted U member 25 extends around the plate or brake shoe members 24. The two legs of member 25 are resiliently pressed together and towards the plate members 24 which latter are then pressed onto disc 20 by means of a bolt 27 and a spring 26. The stirrup member 25 is connected with a stationary part 25' and interlocks the warp beam 2 and the tensioning beam 4. The two legs of member 25 can be forced apart against the ac-

tion of spring 26 whereby the plates 24 are removed from disc 20 so that there is no interlocking of the two beams 2 and 4. Forcing apart of the legs of member 25 is accomplished by a cam 31 which is connected to one end of a rod 28 the other end of which carries a lever 29 which is engaged and operated by a cam 30.

If the lever 7 is turned in the direction of arrow 13 because of a shortening of the warp threads the brake band 14 is loosened and warp beam 2 is freed and turns in the direction of arrow 32 under the influence of the tensioned warp threads 1. The free length of the warp threads between the warp beam 2 and the shed 3 is then increased whereby tensioning lever 7 moves clockwise and the brake effect on beam 2 is increased.

In Figures 4 and 5 an embodiment of the present invention is shown in which the tensioning beam 34 is locked independently from the warp beam 2.

In the machine according to Figs. 4 and 5 the warp threads 1 running off the warp beam 2 pass over the tensioning beam 34 which rotates about the pivots 33. These pivots are supported by means of tensioning beam support lever 35 which swings about axle 36. Fulcrums 33 and 36 are preferably provided with ball-, roller-, or needle-bearings so that the mechanism follows all movements of the warp threads without changing the tension thereof. Lever 35 has an extension 37 which carries a weight 38 which is displaceable along said extension. The end of lever arm 37 is situated between two flat members 39 which are resiliently held together and are pressed against the extension 37 by means of bolt 41 and spring 40. The flat members 39 are interconnected and fixed to a stationary part 43 of the loom by means of a bolt 42. The flat members 39 with their interconnection form an inverted U similar to part 25 in the embodiment of the present invention shown in Figs. 1 to 3. The legs of the U which are resiliently forced together can be spread apart by a wedge member 45 which is disposed at the end of a lever 45' which swings about a stationary fulcrum 44. The wedge member 45 is provided with a roller 46 which rests on a cam 47 which cam is keyed to shaft 48; the latter is driven by the main drive of the loom. Cam 47 is thus adapted to periodically swing lever 45' and wedge 45 upward and in between the members 39 thereby disengaging said members from lever arm 37 and unlocking lever 35, 37.

Shaft 48 carries also a crank or eccentric 49 by means of which the warp beam 2 is periodically locked. For this purpose a rod 50 is connected with eccentric 49; rod 50 is resiliently connected by means of spring 51 and shackle 52 to one end of the brake band 14. The other end of the brake band is connected with a threaded bolt 54 which rests, through the agency of spring 53, on the lever 35 which holds and supports the tensioning beam 34. The brake band 14 engages the brake drum 16 which acts on the warp beam 2 through the intermediary of gear wheels 21 and 22.

The action of the brake depends on the position of lever 35 and also on the position of cam 47. Furthermore, the tension of the brake band is increased periodically during each beat of the reed because of the connection of one end of the band with the crank 49 which end, in the embodiment shown in Figs. 1 to 3, is fixed.

Figure 6 shows in detail the arrangement of the tensioning spring 60 and of the brake spring 70 so that the tension of the warp threads is substantially the same at all possible positions of the tensioning beam 4. The moment of torsion produced by the tensioning spring 60 on the lever 7 should be constant, as far as possible. In order to avoid the use of too large a spring 60 the following construction is proposed: ϕ is the angle enclosed by the direction 68 in which the force of the spring 60 acts and the connecting line between the fulcrum 9 of lever 7, 7' and point 63 at which said force acts on lever 7, 7' and which point is the point of angle ϕ . The influence of the characteristic, i. e. the change of power of spring 60, for example, per inch elongation depends on the size of angle ϕ . This angle can be so chosen that there is a minimum change of the torque produced by spring 60 on lever 7. If angle ϕ amounts to 45° the initial tension of spring 60 must be $r \sin 45^\circ$ where r designates the radius or distance of point 63 from fulcrum 9. This distance is made adjustable.

If the tension of the warp threads is changed solely by tensioning of spring 60 the initial tension is not $r \sin 45^\circ$ and the moment of torsion acting on the tensioning beam 4 is not independent from the position of said beam. The mechanism shown in Fig. 6 assures a satisfactory control of the warp thread tension. The lever 7, 7' is provided with a slot 61 the longitudinal axis of which passes through the center of fulcrum 9. A threaded bolt 62 is provided in said slot which carries a nut 63 having a pivot attached thereto for movably holding one end of rod 64. On the other end of rod 64 acts one end of the spring 60. The other end of said spring rests on the washer 65 which washer rests on stationary member 66 which is provided with a slot 67 for accommodating the rod 64. If it is desired to increase the tension of the warp screw 62 is revolved for moving nut 63 outward, i. e. for increasing radius r and washer 65 is moved upward on member 66 until rod 64 is again in horizontal position. If, as shown in Fig. 6, angle ϕ is 45° member 66 is fixed to a stationary part of the loom in a position perpendicular to rod 64. The initial tension of spring 60 is then $r \sin 45^\circ$ at all tensions of the warp threads. If angle ϕ is not 45° washer 65 does not move in a plane which is perpendicular to rod 64.

In order to eliminate the influence of the brake spring 70 a spring of such character is chosen that the moment of torsion acting on the tensioning beam remains constant as long as the changes of angle β are minor. Angle β is formed by the line of direction of the force of spring 70 acting on pivot 8 and the connecting line between the center of pivot 8 and the center of fulcrum 9.

The brake force is much reduced at diminishing diameter of the warp beam and a large movement of tensioning lever 7 is therefore desired. This is made possible by means of the following mechanism: Spring 70 is so designed as to produce the desired initial force at an angle β . When lever 7 moves to its extreme tensioning position the force of spring 70 changes to produce the maximum desired brake effect. Brake band 72 is not only subjected to the influence of spring 70 but also to the influence of spring 71 which may be replaced by a weight. The initial tension of spring 71 is equal to the smallest force produced by spring 70. The difference between the forces of springs 70 and 71 acts on the brake

band 72; this difference varies between a zero value and the maximum brake force.

The actions of springs 70 and 71 are diagrammatically shown in Figure 7. In this figure the ordinates represent the force of the springs, for example in pounds, and the abscissae the movement or swing of the tensioning lever 7, for example in inches. The inclined line 70' illustrates the force produced by spring 70 at various positions of the tensioning lever 7; the horizontal line 71' shows the force produced by spring 71; the latter force is constant and the same at all positions of lever 7 because one end of spring 71 is stationary and the other connected with brake band 72, i. e. also stationary and the length of spring 71 is always the same. The difference between the forces 70' and 71' acts on brake band 72. The character of spring 70 which is indicated by the inclination of line 70' is such that at the maximum possible movement s of the tensioning beam 7 the force acting on the brake band varies from zero to a value designated by letter p where the force p is the maximum desired brake force.

The relation between the initial tension of the spring for producing the desired warp tension and the angle ϕ at which said spring acts on the tensioning lever 7 is more clearly illustrated in Figs. 8 and 9. In Fig. 8 numeral 90 designates the fulcrum of a tensioning lever 80 the end of which rotatably supports the tensioning beam 92 by means of pivot 91. Lever 80 is provided with an extension 93 which has a plurality of notches 94 for receiving one of the hooked ends of the tensioning spring 95. The axis 99 of spring 95 and the radius r between the center of fulcrum 90 and the point where spring 95 is hooked to extension 93 form an angle ϕ . The other end of spring 95 is also hook-shaped and hooked into one of the notches 97 of a stationary member 96. Notches 97 are disposed along a line 98 which line encloses with the axis of the tensioning spring an angle ψ . The moment of torsion M acting on the lever 80 can be defined by the following equation:

$$M = P r \sin \phi = f a r \sin \phi$$

where

P is the force of the spring,

f is the character of the spring,

a is the initial elongation of the spring,

r is the radius on which the spring acts, and

ϕ is the angle at which the spring acts on the tensioning lever.

The initial elongation a can be expressed by the equation:

$$a = k + r \cos \phi$$

wherein k is a constant; if this expression is used for the value a the change of the moment of torsion at a change of the angle ϕ is:

$$\frac{dM}{d\phi} = f(k r \cos \phi - r^2 (\cos^2 \phi - \sin^2 \phi))$$

The change is a minimum when

$$\frac{dM}{d\phi} \text{ equals zero}$$

i. e. when

$$k = -r \frac{\cos 2\phi}{\cos \phi} \text{ or } a = r \tan \phi \sin \phi$$

If angle ϕ is 45°, k is zero and a equals $r \sin 45^\circ$.

This is the case in the mechanism shown in Fig. 6. In the mechanism shown in Fig. 8,

angle ϕ is larger than 45° ; since k is in proportion to r the end of the spring moves on a straight line having the inclination:

$$\cot \phi = \tan \phi - \frac{1}{\tan \phi}; \psi = \arccot \left(\tan \phi - \frac{1}{\tan \phi} \right)$$

In Fig. 8 the total initial elongation or tension of spring 85 is $r \cos \phi + k$ and the length of the untensioned spring is designated by letter b .

With the arrangement according to the present invention it is possible to adjust the tension of the warp threads 1 so that this tension remains equal and independent from changes of angle ϕ and that without changing the spring.

Figure 9 illustrates another embodiment of the present invention. The tensioning lever 84 which is the equivalent of lever 7 in Fig. 1 swings about fulcrum 82 corresponding to fulcrum 9 in Fig. 1 and carries the tensioning beam 88 corresponding to beam 4 in Fig. 1. Lever 84 has an extension 100 corresponding to extension 53' in Fig. 1 provided with a slot 81 in which rests one end of spring 85 and which has such configuration that there is the following relation between the initial tension a of spring 85 and the angle ϕ formed by the center line of the spring and the line connecting the spring end and fulcrum 82:

$$a = r \tan \phi \sin \phi$$

where the distance a is measured from the involute 83 extending from fulcrum 82.

In the embodiment of the invention according to Fig. 9 spring 85 serves for controlling the brake force of band brake 86. A spring 87 is provided the strength of which is greater than that of spring 85. If the warp threads 1 are too long tensioning beam 88 swings upward about fulcrum 82, the tension of spring 85 is reduced and the braking effect which is the difference between the constant force of spring 87 and the variable force of spring 85 is increased.

Adjustment of the brake force may be made by manipulation of nuts 89.

While I believe the above described embodiments of my invention to be preferred embodiments, I wish it to be understood that I do not desire to be limited to the exact details of design and construction shown and described, for obvious modifications will occur to a person skilled in the art.

I claim:

1. A warp thread supply and tensioning mechanism for power looms including a loom drive, a warp beam, a warp tensioning beam, a brake connected with said warp beam, a periodically acting locking mechanism connected with said tensioning beam and with said loom drive and with said brake and periodically locking said tensioning beam and said brake in their positions before the beat, and connecting means connected with said brake and with said tensioning beam for rendering the operation of said brake dependent on the position of said tensioning beam when said locking mechanism is unlocked.

2. A warp thread supply and tensioning mechanism for power looms including a loom drive, a warp beam, a warp tensioning beam, a brake connected with said warp beam, a periodically acting locking mechanism connected with said tensioning beam, with said loom drive, with said brake and with said warp beam and periodically locking said tensioning beam, said brake and said warp beam, and connecting means connected with said brake and with said tensioning beam

for rendering the operation of said brake dependent on the position of said tensioning beam when said locking mechanism is unlocked.

3. A warp thread supply and tensioning mechanism for power looms including a loom drive, a warp beam, a warp tensioning beam, a movable warp tensioning beam support having locking means connected therewith, a brake connected with said warp beam and being lockingly engaged by said locking means, a periodically acting unlocking mechanism connected with said loom drive and periodically unlocking said locking means and disengaging said locking means from said brake, and connecting means connected with said support and with said brake for rendering the operation of said brake dependent on the position of said tensioning beam when said locking means are unlocked.

4. A warp thread supply and tensioning mechanism for power looms including a loom drive, a warp beam, a warp tensioning beam, a warp tensioning beam support lever having locking means connected therewith, a brake having a brake disc operatively connected with said warp beam and being adapted to be lockingly engaged by said locking means, a periodically acting unlocking mechanism connected with said loom drive and periodically unlocking said locking means and disengaging said locking means from said brake, said brake having a brake band engaging said brake disc and having an end connected with said support lever for rendering the operation of said brake dependent on the position of said support lever when said locking means are unlocked.

5. A warp thread supply and tensioning mechanism for power looms including a loom drive, a warp beam, a warp tensioning beam, a movable warp tensioning beam support having a forked end, a brake connected with said warp beam and having a disc member rotating in the same plane as said support moves and adapted to be lockingly engaged by the prongs of said forked end, a periodically acting unlocking mechanism connected with said loom drive and periodically disengaging the prongs of said forked end from said disc, and brake means connected with said support and with said brake for rendering the operation of said brake dependent on the position of said support when said locking means are unlocked.

6. A warp thread supply and tensioning mechanism for power looms including, in combination, a warp beam, a warp tensioning beam, the warp threads running off from said warp beam passing over said tensioning beam before forming the shed, a tensioning beam support adapted to swing about a stationary fulcrum and swingably supporting said tensioning beam, a guide means longitudinally displaceably connected with said support, a source of power connected with said guide means and swinging said support for pressing said tensioning beam against and thereby tensioning the warp threads, the magnitude of tensioning power depending on the position of said guide means on said support and the line of direction of action of said source of power on said support and the line connecting the point of action of said source on said support and the fulcrum of said support forming an angle which is smaller than 60° and which remains substantially the same at all positions of said guide means relatively to said support.

7. A warp thread supply and tensioning mechanism for power looms including a warp beam,

a warp tensioning beam, the warp threads running off from said warp beam and passing over said tensioning beam before forming the shed, a tensioning beam support swinging about a stationary fulcrum and swingably supporting said tensioning beam, a spring connected with said support and swinging said support and pressing said tensioning beam against and thereby tensioning the warp threads, the initial elongation of said spring being $r \sin \phi \tan \phi$ whereby ϕ is the angle formed by the line of direction of action of said spring on said support and the line connecting the point of action of said spring on said support and the fulcrum of said support, and r is the distance between said point of action and said fulcrum.

8. A warp thread supply and tensioning mechanism for power looms including a warp beam, a warp tensioning beam, the warp threads running off from said warp beam passing over said tensioning beam before forming the shed, a tensioning beam support adapted to swing about a stationary fulcrum and swingably supporting said tensioning beam, said support having a longitudinal guide, and a tensioning means connected with and being displaceable along said guide and swinging said support and pressing said tensioning beam against and thereby tensioning the warp threads.

9. A warp thread supply and tensioning mechanism for power looms including a warp beam, a warp tensioning beam, the warp threads running off from said warp beam passing over said tensioning beam before forming the shed, a tensioning beam support adapted to swing about a stationary fulcrum and swingably supporting said tensioning beam, said support having a longitudinal guide, and a tensioning means connected with and being displaceable along said guide and swinging said support and pressing said tensioning beam against and thereby tensioning the warp threads, the line of direction of action of said tensioning means on said support forming with the longitudinal axis of said guide an angle of substantially 45°.

10. A warp thread supply and tensioning mechanism for power looms including a warp beam, a warp tensioning beam, the warp threads running off from said warp beam passing over said tensioning beam before forming the shed, a tensioning beam support adapted to swing about a stationary fulcrum and swingably supporting said tensioning beam, said support having a longitudinal guide extending radially from the fulcrum of said support, and a tensioning means having an end connected with and being displaceable along said guide and swinging said support and pressing said tensioning beam against and thereby tensioning the warp threads, and having a stationary part which is movably connected with a stationary part of said loom, the line of action of said tensioning means moving parallel to itself upon displacement of said end of said tensioning means along said guide and of said stationary part.

11. A warp thread supply and tensioning mechanism for power looms including a warp beam, a warp tensioning beam, the warp threads running off from said warp beam and passing over said tensioning beam before forming the shed, a tensioning beam support swinging about a stationary fulcrum and swingably supporting said tensioning beam, a brake connected with said warp beam, brake actuating means connected with said brake and said support, and a

tensioning means connected with a stationary part of said loom and with said actuating means.

12. A warp thread supply and tensioning mechanism for power looms including a warp beam, a warp tensioning beam, the warp threads running off from said warp beam and passing over said tensioning beam before forming the shed, a tensioning beam support swinging about a stationary fulcrum and swingably supporting said tensioning beam, a tensioning means connected with said support and swinging said support and pressing said tensioning beam against and thereby tensioning the warp threads, a brake connected with said warp beam, brake actuating means connected with said brake and with said support, the direction of action of said actuating means being substantially opposite to that of said tensioning means and including with the line interconnecting the point of action of said support on said actuating means and said fulcrum an angle which is smaller than 30°.

13. A warp thread supply and tensioning mechanism for power looms including a warp beam, a warp tensioning beam, the warp threads running off from said warp beam and passing over said tensioning beam before forming the shed, a tensioning beam support swinging about a stationary fulcrum and swingably supporting said tensioning beam, a brake connected with said warp beam, and a tensioning and brake actuating means connected with said support and with said brake and actuating said brake and also swinging said support and pressing said tensioning beam against and thereby tensioning the warp threads.

14. A warp thread supply and tensioning mechanism for power looms including, in combination, a loom drive, a warp beam, a warp tensioning beam, a tensioning beam support adapted to swing about a fulcrum and swingably supporting said tensioning beam, a source of power connected with said support and swinging said support for pressing said tensioning beam against and thereby tensioning the warp threads, the line of direction of action of said source of power on said support and the line connecting the point of action of said source on said support and the fulcrum of said support forming an angle which is smaller than 60°, a periodically acting locking mechanism connected with said tensioning beam and with said loom drive and periodically locking said tensioning beam in its position before the beat.

15. A warp thread supply and tensioning mechanism for power looms including a warp beam, a warp tensioning beam, the warp threads running off from said warp beam and passing over said tensioning beam before forming the shed, a tensioning beam support swinging about a stationary fulcrum and swingably supporting said tensioning beam, a tensioning means connected with said support and swinging said support and pressing said tensioning beam against and thereby tensioning the warp threads, a brake connected with said warp beam, brake actuating means connected with said brake and with said support and adapted to exert torque thereon, the direction of action of the torque effected by said actuating means on said support being the same as that of said tensioning means.

16. A warp thread supply and tensioning mechanism for power looms including a warp beam, a warp tensioning beam, the warp threads running off from said warp beam and passing over said tensioning beam before forming the

shed, a tensioning beam support swinging about a stationary fulcrum and swingably supporting said tensioning beam, a tensioning means connected with said support and swinging said support and pressing said tensioning beam against and thereby tensioning the warp threads, a brake connected with said warp beam, brake actuating means connected with said brake and with said support and adapted to exert torque thereon, the direction of action of the torque effected by said actuating means on said support being substantially opposite to that of said tensioning means.

17. A warp thread supply and tensioning mechanism for power looms including a warp beam, a warp tensioning beam, the warp threads running off from said warp beam and passing over said tensioning beam before forming the shed, a tensioning beam support swinging about a stationary fulcrum and swingably supporting said tensioning beam, a brake connected with said warp beam, brake actuating means connected with said brake and said support, and a spring interposed in said actuating means between said support and said brake, the line of direction of action of said brake actuating means on said support and the line connecting the point of action of said brake actuating means on said support and the fulcrum of said support forming an angle which is smaller than 30°.

18. A warp thread supply and tensioning mechanism for power looms including, in combination, a warp beam, a warp tensioning beam, the warp threads running off from said warp beam passing over said tensioning beam before forming the shed, a tensioning beam support adapted to swing about a stationary fulcrum and swingably supporting said tensioning beam, a guide means movably connected with said support and being displaceable along a line extending substantially radially from said stationary fulcrum, a source of power connected with said guide means and swinging said support for pressing said tensioning beam against and thereby tensioning the warp threads, the magnitude of tensioning power depending on the position of said guide means on said support and the line of direction of action of said source of power on said support and the line connecting the point of action of said source on said support and the fulcrum of said support forming an angle which is smaller than 60° and which remains substantially the same at all positions of said guide means relatively to said support.

19. A warp thread supply and tensioning mechanism for power looms including, in combination, a warp beam, a warp tensioning beam, the warp threads running off from said warp beam passing over said tensioning beam before forming the shed, a tensioning beam support adapted to swing about a stationary fulcrum and swingably supporting said tensioning beam, a guide means longitudinally displaceably connected with said support, a source of power connected with said guide means and swinging said support for pressing said tensioning beam against and thereby tensioning the warp threads, the magnitude of tensioning power depending on the position of said guide means on said support and the line of direction of action of said source of power on said support and the line connecting the point of action of said source on said support and the fulcrum of said support forming an angle which is smaller than 60° and which remains substantially the same at all positions of said guide means relatively to said support, and

arresting means operatively connected with said tensioning beam support and with the loom drive and including periodically acting arresting means actuating means periodically arresting said tensioning beam support in its position before the beat.

20. A warp thread supply and tensioning mechanism for power looms including, in combination, a warp beam, a warp tensioning beam, the warp threads running off from said warp beam passing over said tensioning beam before forming the shed, a tensioning beam support adapted to swing about a stationary fulcrum and swingably supporting said tensioning beam, a guide means longitudinally displaceably connected with said support, a source of power connected with said guide means and swinging said support for pressing said tensioning beam against and thereby tensioning the warp threads, the magnitude of tensioning power depending on the position of said guide means on said support, the line of direction of action of said source of power on said support and the line connecting the point of action of said source on said support and the fulcrum of said support forming an angle which is smaller than 60° and which remains substantially the same at all positions of said guide means relatively to said support, brake means connected with said warp beam, and brake means actuating means connected with said brake means and with said tensioning beam support and being actuated by said support whenever said tensioning beam is moved in a direction for tensioning the warp threads whereby rotation of said warp beam is reduced whenever the warp threads are tensioned.

21. A warp thread supply and tensioning mechanism for power looms including, in combination, a warp beam, a warp tensioning beam, the warp threads running off from said warp beam passing over said tensioning beam before forming the shed, a tensioning beam support adapted to swing about a stationary fulcrum and swingably supporting said tensioning beam, a guide means longitudinally displaceably connected with said support, a source of power connected with said guide means and swinging said support for pressing said tensioning beam against and thereby tensioning the warp threads, the magnitude of tensioning power depending on the position of said guide means on said support and the line of direction of action of said source of power on said support and the line connecting the point of action of said source on said support and the fulcrum of said support forming an angle which is smaller than 60° and which remains substantially the same at all positions of said guide means relatively to said support, arresting means operatively connected with said tensioning beam support and with the loom drive and including periodically acting arresting means actuating means periodically arresting said tensioning beam support in its position before the beat, brake means connected with said warp beam, and brake means actuating means connected with said brake means and with said tensioning beam support and being actuated by said support whenever said tensioning beam is moved in a direction for tensioning the warp threads whereby rotation of said warp beam is reduced whenever the warp threads are tensioned.

22. A warp thread supply and tensioning mechanism for power looms including, in combination, a warp beam, a warp tensioning beam, the warp threads running off from said warp beam pass-

ing over said tensioning beam before forming the shed, a tensioning beam support adapted to swing about a stationary fulcrum and swingably supporting said tensioning beam, a guide means longitudinally displaceably connected with said support, a source of power connected with said guide means and swinging said support for pressing said tensioning beam against and thereby tensioning the warp threads, the magnitude of tensioning power depending on the position of said guide means on said support and the line of direction of action of said source of power on said support and the line connecting the point of action of said source on said support and the fulcrum of said support forming an angle which is smaller than 60° and which remains substantially the same at all positions of said guide means relative-

ly to said support, brake means connected with said warp beam, and brake means actuating means connected with said brake means and with said tensioning beam support and being actuated by said support whenever said tension beam is moved in a direction for tensioning the warp threads whereby rotation of said warp beam is reduced whenever the warp threads are tensioned, and arresting means operatively connected with said tensioning beam support, with said warp beam and with the loom drive and including periodically acting arresting means actuating means periodically arresting said tensioning beam support and said warp beam in their position before the beat.

ALBERT MOESSINGER.
